(57) **CLAIM**

The ornamental design for a card deck box, as shown and described.

DESCRIPTION

FIG. 1 is a front perspective view of a card deck box, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The dash-dash broken lines in the drawings represent stitching that do form part of the claim design. The dot-dot broken lines shown on the interior area in FIGS. 1 and 7, depict portions of the card deck box that form no part of the claimed design.
